UNITED STATES PATENT OFFICE.

CARL VALENTIN, OF STUTTGART, GERMANY.

AUTOMATIC BOBBIN-CHANGING DEVICE FOR LOOMS.

Application filed October 9, 1926, Serial No. 140,546, and in Germany May 29, 1925.

Automatic bobbin changing devices for looms of the kind with a fixed frame magazine and a rotating thread holder are known. The fixed frame magazines of this known kind had generally the form of an inclined bobbin runway, which made it necessary to guide the threads by the aid of card bands, sprocket chains, belts or the like, which owing to the unavoidable vibration of the looms were caused to oscillate and execute movements of their own, whereby the threads suspended therefrom became twisted or tangled which easily caused breakage of the threads. The suggestion has been made to construct the fixed frame magazine as part of a circle, about the central axis of which the thread guiding disc, which is constructed in the form of a circular disc, makes a partial rotation every time a bobbin is changed, while the bobbins slide forwards in the fixed magazine. The apparatus was also so constructed that the concave opening of the circular shaped magazine was turned towards the weaver's seat and the magazine projected towards the side of the loom over the slay or batten. For overshot looms such an arrangement cannot be used, because the path for the picker arm is then no longer free.

The object of the present invention is to provide a bobbin changing device which can also be used for overshot looms and overcome the above mentioned disadvantages. The invention is substantially characterized by the fact that the convex side of the partly circular shaped magazine is turned towards the weaver, so that the slay or batten is brought from the concave side of the magazine to the lowermost open point of the magazine and the path for the overshot arm is left free. The invention is also characterized by an improved device for feeding in the bobbins and for securely holding a bobbin until the picker is again in position of rest.

In the accompanying drawing:—

Fig. 1 is a side elevation of the apparatus, and

Fig. 2 is a plan view thereof.

In the semi-circular fixed frame 1 lie the bobbins 2, the ends of the threads from which pass over the guide disc 3 and are affixed thereto at 4. The operating shaft 5 carries a lever 6 which is connected by means of a connecting rod 7 to the shuttle feeler 8 which is constructed in the form of a bell

crank. This shuttle feeler, if the shuttle is not properly positioned into the shuttle box, is so set that it both prevents any change of bobbin and any further movement of the disc 3. The shuttle feeler 8 is adapted to rock or pivot on the bolt 9 and has on its vertical arm a lug with a curved slot 10 in it, through which a bolt 11 on the introducing lever 12 fits. This introducing lever has a frog-like end in which the bunter 20, which vibrates to and fro with the slay or batten, can engage when the change of bobbin is initiated. The introducing lever also carries an angle-shaped arm 13. The feed lever 14 for the intermittent rotation of the disc 3 is mounted to move longitudinally at 15 and has on its horizontal limb 16 a notch 16' and on its vertical limb at the top a feed pawl 17, connected by a pivoted lever and a locking pawl 18 for operating the ratchet wheel 19, which is connected by the shaft 20 to the thread guiding disc 3.

When a change of bobbins is initiated in the well-known way and the shaft 5 makes a partial rotation in the direction of the arrow (Fig. 1), the lever 6 swings upwards and by means of the connecting rod 7 draws the horizontal limb of the angularly shaped shuttle feeler also upwards, whereby the vertical limb of the bell-crank lever 8 swings rearward and downward. In this way the lever 12, which is connected by the bolt 11 to the bell-crank lever 8, is brought within range of the bunter 20.

When the loom slay or batten moves forward, the bunter 20 bears against the frog of the lever 12 and pushes it forward. By drawing down the lever 12 the arm 13 connected thereto moves into the notch 16' of the feed or ratchet lever 14, 16, and consequently the lever is moved in the bearing 15 forward indirectly by the slay or batten. The pawl 17 is thereby brought into operation that is to say, it sets itself behind the next tooth of the ratchet wheel. The forward feed of the ratchet wheel and of the thread-guiding disc connected to it only takes place after the change of bobbins has been completed by the pressure of the lever 21 (connected to the shaft 5) on the feed lever 14 and moreover at the instant the bobbin in the fixed bobbin frame slides downwards.

If a shuttle has not been properly positioned in the shuttle box, the shuttle presses the feeler 8 out of the dotted position into

that shown by full lines, when the slay or batten moves forwards, whereby the initial movement for operating the thread-holding disc 3 is arrested and no change of bobbin 5, can take place.

I claim:—

1. In automatic bobbin changing devices for looms, a fixed partly circular frame magazine with its convex side nearest the weaver, a rotating thread guide consisting of a circular disc running concentrically with the axis of the magazine, mechanism for imparting a partial rotation to the disc and for changing the bobbins comprising an angle-shaped lever, an introducing ram pivoted to one end of said lever, a lever arm with a frog-like end and an angle lug, a bunter on the loom slay, a pawl and ratchet mechanism for turning the disc, a sliding rod operating said pawl mechanism and having a shoulder engaging the angle lug of the lever arm, and a shuttle feeler with a slotted lug engaging the lever arm to support it in its neutral position, or to bring it down into the position opposite or in alignment with the bunter when requiring to change a bobbin and rotate the thread guide. 45

2. In automatic bobbin changing devices for looms, a fixed magazine, a rotating thread guide consisting of a circular disc running concentrically with the axis of the magazine, means for imparting a partial rotation to the disc and for changing the bobbins comprising a lever, an introducing ram pivoted to one end of said lever, a lever arm with a frog-like end and an angle lug, a bunter on the loom slay, a pawl and ratchet mechanism for turning the disc, a rod operating said pawl and ratchet mechanism and having a shoulder engaging the angle lug of the lever arm, and a shuttle feeler to support the lever arm in its neutral position, or to bring it down into position opposite or in alignment with the bunter when requiring to change a bobbin and rotate the thread guide. 65

20 25 30 35 40 45 50 55 60 65

3. In automatic bobbin changing devices for looms, a fixed magazine, a rotating thread guide consisting of a circular disc running concentrically with the axis of the magazine, mechanism for imparting a partial rotation to the disc and for changing the bobbins comprising an angle shaped lever, an introducing ram pivoted to one end of said lever, a lever arm with a frog-like end and an angle lug, a bunter on the loom slay, a pawl and ratchet mechanism for turning the disc, a rod operating said pawl and ratchet mechanism and having a shoulder engaging the angle lug of the lever arm, and a shuttle feeler to support the lever arm in its neutral position, or to bring it down into position opposite or in alignment with the bunter when requiring to change a bobbin and rotate the thread guide. 55

In testimony whereof I affix my signature.

CARL VALENTIN.

said lever, a lever arm with a frog-like end and an angle lug, a bunter on the loom slay, a pawl and ratchet mechanism for turning the disc, a sliding rod operating said pawl mechanism and having a shoulder engaging the angle lug of the lever arm, and a shuttle feeler with a slotted lug engaging the lever arm to support it in its neutral position, or to bring it down into the position opposite or in alignment with the bunter when requiring to change a bobbin and rotate the thread guide. 40 45

3. In automatic bobbin changing devices for looms, a fixed magazine, a rotating thread guide consisting of a circular disc running concentrically with the axis of the magazine, means for imparting a partial rotation to the disc and for changing the bobbins comprising a lever, an introducing ram pivoted to one end of said lever, a lever arm with a frog-like end and an angle lug, a bunter on the loom slay, a pawl and ratchet mechanism for turning the disc, a rod operating said pawl and ratchet mechanism and having a shoulder engaging the angle lug of the lever arm, and a shuttle feeler to support the lever arm in its neutral position, or to bring it down into position opposite or in alinement with the bunter when requiring to change a bobbin and rotate the thread guide.

In testimony whereof I affix my signature.

CARL VALENTIN.
